WILLIAM R. MANLEY, OF NEW YORK, N. Y., ASSIGNOR TO HIMSELF AND WILLIAM H. WEBB, OF SAME PLACE.

Letters Patent No. 88,052, dated March 23, 1869.

IMPROVEMENT IN PADDLE-WHEELS.

The Schedule referred to in these Letters Patent and making part of the same.

To all whom it may concern:

Be it known that I, WILLIAM R. MANLEY, of the city, county, and State of New York, have invented a new and useful Improvement in Feathering Paddle-Wheels for steamships; and that the following is a full, clear, and exact description and specification of my invention.

The object of my invention is to enable the feathering, or controlling-mechanism of the paddles of the wheel to adapt itself to the movements of the paddle-wheel and its shaft, so as to maintain its proper relation to the paddles, however much the paddle-wheel and its shaft may vary their positions by the straining of the ship in a sea-way or otherwise. To this end,

My invention consists in arranging, or mounting the eccentric of the controlling-frame upon the paddle-wheel shaft, (so that the said eccentric and frame move with the paddle-wheel and its shaft,) and in combining the said eccentric with the ship, by means of a flexible connection, which, while preventing the eccentric from turning with the shaft, permits the eccentric to move laterally or radially, in all directions, with said shaft, and, therefore, to maintain its proper relationship to the paddles.

In order that my said invention may be fully understood, I have represented, in the accompanying drawing, a sufficient portion of a feathering paddle-wheel, embodying it, to illustrate the invention, and will proceed to describe the same.

Figure 1 represents a section of the paddle-wheel, at the axis of the shaft, the shaft, arms, and paddles being represented in elevation.

Figure 2 represents a side view of a portion of the paddle-wheel.

The arms A A of the paddle-wheel are secured to hubs B B, in the usual manner, and the hubs B B are mounted upon and secured to the paddle-wheel shaft C.

Each paddle, or paddle-board D, is secured to a rock-shaft, E, which is constructed to rock in boxes G G, secured to the wheel-arms A.

One end of each rock-shaft E is fitted with a crank, F, and the crank-pins α of the whole series of rock-shaft cranks F are connected with the arms I of the controlling-frame to rock the rock-shafts E of the paddle-boards, as the wheel revolves, and the controlling-frame revolves with it.

The arms of the controlling-frame are secured, at their inner ends, to a ring-hub, K, which is fitted to turn upon the eccentric M, which, by its eccentricity to the paddle-wheel shaft C, causes the arms I of the controlling-frame to rock the rock-shafts E of the paddle-boards, as the wheel revolves, and the controlling-frame revolves with it.

The eccentric M is mounted upon the paddle-wheel

shaft C, which turns in a bearing, or box w, in said eccentric.

The eccentric is also fitted with an arm, N, whose outer end is connected with the side of the ship by means of a link, P, pivoted at one end to a plate, Q, that is bolted to the side of the ship, and pivoted at the other end to the eccentric-arm N.

As the arm N and link P, thus arranged, constitute a flexible connection with the side of the ship, the eccentric may move radially in any direction with the paddle-shaft on which it is mounted, but is prevented from turning; hence the controlling-frame is forced to maintain its relation to the paddles, by reason of its being mounted upon the paddle-shaft, and, on the other hand, it is prevented from turning, and yet permitted to move laterally with the said shaft, by reason of the flexible connection between the eccentric and the ship.

Having thus described one of the modes in which I have applied the principle of my invention, I declare that I do not limit my invention to that mode, as the construction of the wheel and controlling-mechanism may be greatly varied, without changing the invention. Thus, for example, the construction of the flexible connection between the eccentric M and the ship may be changed, by forming the arm N with a slot in its end, (as represented in blue lines, in fig. 2,) and by applying a pin, (also represented in blue lines,) to the ship's side, so that the end of the arm may play upon said pin as the eccentric moves radially with the paddle-wheel shaft, while the pin prevents the eccentric from turning with the said shaft.

I prefer to apply the eccentric and controlling-frame to the inner side of the paddle-wheel, or that next the ship; but it may be applied to the outer side thereof, and the flexible connection may take hold of the guard of the wheel, and be connected with the ship through it.

What I claim as my invention, and desire to secure by Letters Patent, is—

The arrangement and combination of the eccentric of the controlling-frame of the paddles of a feathering paddle-wheel with the paddle-shaft, and with the ship, in such manner that said eccentric is both supported upon the paddle-shaft and connected with the ship, by means of a flexible connection, substantially as before set forth.

In testimony whereof, I have hereto set my hand, this 3d day of September, A. D. 1869.

W. R. MANLEY.
